DESIGN FOR AN AIRPLANE

James J. Dickson, Chicago, Ill., and Robert
W. Huzzard, York, Pa.

Application March 12, 1945, Serial No. 118,406

Term of patent 3½ years

(Cl. D71—1)

To all whom it may concern:

Be it known that we, James J. Dickson and Robert W. Huzzard, citizens of the United States, residing in Chicago, in the county of Cook and State of Illinois, and in York, in the county of York and State of Pennsylvania, respectively, have invented a new, original, and ornamental Design for an Airplane, of which the following is a specification, reference being had to the accompanying drawings forming a part thereof, wherein:

Fig. 1 is a front elevational view of an airplane showing our new design, the airplane proper being shown in dotted lines and the cargo and passenger containers being shown in full lines. The wing tips are broken away for convenience of illustration.

Fig. 2 is a side elevational view looking toward the outboard or door side of the right hand cargo and passenger container shown in Fig. 1.

Fig. 3 is a side elevational view looking toward the inboard or window side of the left hand cargo or passenger container shown in Fig. 1.

Fig. 4 is a perspective view of an airplane of the new design looking toward the underside thereof, the airplane proper being shown in dotted lines, and the attachable cargo and passenger container units being shown in full lines.

The cargo and passenger container of Fig. 3 is substantially identical with that of Fig. 2 except that the door and window sides are reversed; that is, the door side of the container of Fig. 3 is on the opposite side of the container from that illustrated in Fig. 3, the door side of the container of Fig. 3 having an appearance similar to Fig. 2; and the window side of the container of Fig. 2 is on the opposite side of the container of said figure from that illustrated in Fig. 2, the window side of the container of Fig. 2 having an appearance similar to that of the container of Fig. 3.

We claim:

The ornamental design for an airplane, substantially as shown and described.

JAMES J. DICKSON.

ROBERT W. HUZZARD.
